ABSTRACT OF THE DISCLOSURE

A ladder consisting of side rails each constructed from a pair of plastic rods joined in parallel relationship to each other by metal plates engaging the rods and the metal plates of one side rail joined by rungs to the metal plates of the other side rail.

This invention relates to an improved ladder and the method of its manufacture.

Ladders of various kinds are known and ladders of fixed length or of the extension type have been made from timber or metal.

When ladders are required to be movable for use at various places, it is essential that these ladders be as light as possible. In some cases, such as for use by electric supply authorities, it is also essential that the ladders be non-electrical conductors. Wooden ladders are more favoured by electric supply authorities than are metal ladders.

Many attempts have been made to make a ladder from plastic but the cost of such ladders have been prohibitive. Ladders have been made by using channel shape fibre glass side rails to reduce the quantity of plastic but these have also been found to be too costly. Many problems have been met in trying to utilise a combination of metal and plastic in ladder manufacture. The main problem has been to find suitable means of interlocking the metal and the plastic in a ladder construction.

The objects of this invention are to provide a ladder made from part metal and part plastic.

According to this invention an improved ladder may be said to comprise plastic side rail members connected by metal plates to rungs.

It is preferred that each plastic side rail member be composed of two fibre glass plastic rods of circular cross section. It is not essential that rods be used because tubular sections could also be used.

For the invention to be more clearly understood, an embodiment of the invention is described hereafter in some detail with reference to, and as illustrated in the accompanying drawings, in which:

FIG. 1 shows perspective view of a section of the ladder and,

FIG. 2 is a cross-sectional view showing a metal plate on each end of a rung engaged in the slots of the side rail rods.

In this embodiment each side rail 10 of the ladder 12 consists of two three quarter inch diameter fibre glass rods 13 slotted at spaced intervals along their length. The distance between the centre line of one slot to the centre line of an adjacent slot in each rod 13 is equal to the centre line distance between the rungs of the ladder. In this particular embodiment the length of the slots is five and a half inches. The width of the slots are of size to accommodate the thickness of metal plates 14 (which in this embodiment is 12 B.S.G. commercial aluminium plate) and these plates 14 are secured by welding or the like to tubular rungs 15. Each metal plate 14 at one end

2

of the rung 15 is secured by an epoxy resin to a slot 16 of each of two of the fibre glass rods 13 so that the two fibre glass rods are held in parallel spaced relationship to each other and thereby form one side rail 10 of the ladder 12. Similarly the metal plates 14 at the other end of the rungs are secured to the slots of the other two fibre glass rods 13.

To improve the bond between the metal plates 14 and the fibre glass plastic rods 13 the portion of the metal plates, which is enclosed within the slot 16 of the plastic rod, is treated by solvent cleaning, sand blasting or chemical pickling. The portion of the metal plate which is to be closed may be apertured at one or more places to thereby allow a slug of epoxy resin to extend through the aperture from the walls of the slot.

The slots may be readily formed by a milling and/or slotting machine.

A method of making a ladder according to the invention may be said to comprise the steps of welding a metal plate one to each end of, and transverse to the longitudinal axis of a metal rung, forming slots in four plastic rods at spaced intervals along their length, the width of said slots being substantially equal to the thickness of said metal plates, positioning the plastic rods such that the slots in said rods are engaged by the metal plates to thereby form two side rails of the ladder and said metal plates secured to said side rails by an epoxy resin previously applied to said slots.

When the metal plates 14 and rungs 15 are Duralumin or the like it has been found that the ladder so formed has a weight approximately two thirds that of a wooden ladder of equivalent size. As the metal parts of the ladder do not form a continuous path throughout the length of the ladder, the ladder has the required non-electrical conductivity characteristics.

Of course, it will be realised that two separate ladders of this invention may be arranged together in the well known extension ladder combination.

Thus it will be seen that the invention has provided a lightweight ladder of considerable merit.

What I claim is:

1. A ladder comprising electrically non-conductive plastic side rails, each side rail consisting essentially of a pair of fibre glass rods held in spaced relationship to each other by metal plates having oppositely disposed edge portions fixedly engaging matching longitudinal slots in said fibre glass rods at spaced intervals along the length of each fibre glass rod, said edge portions being bonded to the interior surface of said longitudinal slots by an epoxy resin; and metal rungs connecting the metal plates of one side rail to the corresponding metal plates of the other side rail.

2. A ladder according to claim 1 in which the fibre glass rods are of circular cross-section.

3. A ladder according to claim 1 in which the metal plates are commercial aluminium plate and the rungs are tubular aluminium and are welded to the plates.

4. A ladder according to claim 1 in which the edge portion of the metal plates engaging the slots in the fibre glass rods has been specially prepared to provide an improved bond with epoxy resin by a process of either solvent cleaning, sand blasting, chemical pickling, being apertured in at least one place, being indented in at least one place, or a combination thereof, before being bonded by said epoxy resin to the interior surface of said longitudinal slot to effect a stronger fixed engagement therewith.

5. A method of making a ladder comprising the steps of:

(a) welding metal plates one to each end of, and

- transverse to, the longitudinal axis of at least one metal rung;
- (b) forming slots in four plastic rods at spaced intervals along their length, the slots being on the same side of said plastic rods, the width of said slots being substantially equal to the thickness of said metal plates;
- (c) applying epoxy resin to the internal surfaces of said slots;
- (d) positioning the plastic rods such that the slots containing said epoxy resin in respective pairs of said rods are engaged by the respective metal plates to thereby form two side rails of the ladder, said side rails being secured together by said at least one metal rung; and
- (e) allowing said epoxy resin to cure whereby said

ladder becomes a unitary, electrically non-conducting ladder.
